(57) **CLAIM**

The ornamental design for a bucket bracket, as shown and described.

DESCRIPTION

FIG. 1 is an overall perspective view of a bucket bracket;

FIG. 2 is an enlarged bottom perspective view thereof;

FIG. 3 is a top plan view thereof;

FIG. 4 is a front elevation view thereof;

FIG. 5 is a right side elevation view thereof;

FIG. 6 is a rear elevation view thereof;

FIG. 7 is a left side elevation view thereof; and,

FIG. 8 is a bottom plan view thereof.

The broken line showing of a bucket is for illustrative purposes only and forms no part of the claimed design.
